BLOCKER AND COIL HANDLING DEVICE

Louis Leroy, Chicago, and Frank J. Wood, River-side, Ill., assignors to Goodman Manufacturing Company, Chicago, Ill., a corporation of Illinois

Application April 9, 1942, Serial No. 438,248.

8 Claims. (Cl. 242—81)

1

This invention relates to improvements in blockers and coil handling devices particularly adapted for use in conjunction with a slitter of the type which longitudinally slits a coil of metal into a plurality of strips.

Heretofore the recoiling of slit metal has been attained by securing all of the ends of the strips to a common spool or block with circular spacers between the strips. This method necessitates the hooking of each individual strip into a slot in the block and placing the separate spacers between the strips, and after the strips are coiled, the spacers and coils must be removed singly while holding each coil by hand until banded, to prevent its springing open. This takes considerable time and rehandling of spacers. Also, in slitting strip metal, the burrs along the edges of the metal will extend in opposite directions from each adjacent strip, so the burrs of one strip will extend upwardly as it comes from the slitter and the burrs of the next strip will extend downwardly. When the strip is coiled it is desirable that all of the burrs extend either towards the inside or outside of the coils. This is not possible where a single block is used for recoiling.

Individual blocks for each strip have been used in an attempt to overcome these difficulties, but these individual blocks have not remedied the situation to any great extent.

The device of our invention has as its principal objects to overcome these difficulties by providing a novel and simplified form of block and guide arrangement, so arranged that the strips and blocks are convenient to the operator and can be inserted and secured to the strip coiling block with a minimum amount of effort and be wound in the desired direction, together with a means for removing the coils as a group and keeping them in this relation until properly banded and ready for storage or further treatment.

A more specific object of our invention is to provide a novel form of blocker and coil handling device adapted to receive and simultaneously coil a plurality of strips of metal as they come from a slitter, which includes a pair of coiling blocks arranged to simultaneously coil alternate strips of metal and permit the coils to be removed from the ends of the coiling blocks, together with an improved guide means for guiding alternate strips of metal onto the coiling blocks, which also serves to remove the coils from the ends of the coiling blocks onto a coil transferring device where they may be transferred for storage or further treatment.

Other objects of our invention will appear from

2

time to time as the following specification proceeds and with reference to the accompanying drawings wherein:

Figure 1 is a plan view of a coil handling device constructed in accordance with our invention and shown in conjunction with a slitter;

Figure 2 is an enlarged view in side elevation of the device shown in Figure 1, with certain parts shown in longitudinal section;

Figure 3 is an enlarged transverse sectional view looking in a direction towards the coil blockers and showing certain details of the coil spacing and transferring mechanism;

Figure 4 is a transverse sectional view drawn to a smaller scale than Figure 3 and showing the coil push-off mechanism in a fully extended position;

Figure 5 is an enlarged detail transverse sectional view showing certain details of the drive to the blockers;

Figure 6 is an enlarged fragmentary plan view, with certain parts broken away and certain other parts shown in horizontal section, illustrating the drive to the coil blocks and certain details of the coil spacing and transferring mechanism;

Figure 7 is an end view of one of the collapsible blocks for coiling the strip metal;

Figure 8 is a transverse sectional view taken through the coil block shown in Figure 10;

Figure 9 is an enlarged detail transverse sectional view showing certain details of the hold-down means for the ends of the coils;

Figure 10 is a fragmentary sectional view taken substantially along lines 10—10 of Figure 7;

Figure 11 is an enlarged detail fragmentary longitudinal sectional view showing certain details of the clamping means for the ends of the coils;

Figure 12 is an enlarged fragmentary sectional view showing certain other details of the clamping mechanism for the ends of the coils, not shown in Figure 11;

Figure 13 is an enlarged detail view showing certain details of the mechanism for expanding the block;

Figure 14 is an enlarged fragmentary longitudinal sectional view illustrating certain details of the coil spacing means and the hold-down means for the ends of the coil;

Figure 15 is an enlarged detail fragmentary transverse sectional view illustrating certain details of the spacing and guiding means for the coils;

Figure 16 is an enlarged detail view showing

certain details of the mechanism for moving the coil transferring car; and

Figure 17 is a detail view showing certain details of the coil supporting sector on the transfer car.

In the embodiment of my invention illustrated in the drawing, a blocker generally indicated by reference character 10 is provided. Said blocker includes two vertically spaced power driven collapsible coil blocks 11, 11, adapted to simultaneously coil a plurality of strips of metal as they come from a slitter generally indicated by reference character 12. Said blocker also includes strip spacing and push-off means 13 adapted to space the strips of metal as they are wound on said blocks and to transfer the coiled strips of metal to a coil supporting and transfer car 14.

The slitter 12 may be of any well known type which is adapted to longitudinally slit strip metal into a plurality of narrow strips. A pair of guide rolls 15, 15 are provided at the discharge end of said slitter, to guide the metal over a collapsible guide plate 16 and upwardly or downwardly to the blocks 11, 11. Said blocks are adapted to have alternate strips of the slit metal detachably secured thereto, for separately coiling said strips of metal and permitting them to be transferred therefrom onto the transfer car 14, by the coil transferring mechanism 13.

The blocks 11, 11 are of a collapsible type and each of said blocks is adapted to grip the ends of the strips of metal when inserted in a slot 17, extending along its face. Said blocks are each provided with clamping means for gripping the ends of the strips, which is so arranged as to permit the metal to be removed from the end of the block when collapsed, by sliding it along the block by the push-off means 13 without removing the leading end of the metal from said slot, as will more clearly appear as this specification proceeds. Said blocks, as herein shown, are mounted on vertically spaced parallel shafts 19, 19, the lower of which shafts is spaced a slight distance in advance of said upper shaft for increasing the accessibility to each of said blocks. Said shafts are journaled in and project from a housing 20, mounted on a base frame 21, for the blocker. The arrangement is such that said blocks, along with their supporting shafts may readily be removed from the housing 20, so different diameters of blocks may be used to take care of different thicknesses of metal.

The drive to the shafts 19, 19 and collapsible blocks 11, 11 includes a motor 23, mounted on the frame 21. Said motor has driving connection with a variable speed reduction drive indicated generally by reference character 24, through a vari-torque coupling 25 and a V-belt drive 26. The vari-torque coupling 25 may be of a type similar to that illustrated and described in Patent No. 2,135,929 which issued to Frank J. Wood on November 8, 1938, and is adapted to automatically vary the speed of the shafts 19, 19 as the strip metal is wound on the blocks 11, 11 and the torque thereon increases, to provide a constant pull on the strip metal during the entire winding operation. Said variable speed reduction drive 24 may be of any well known form, which is manually adjustable to vary the winding speed of the blocks 11, 11, and is not herein shown or described in detail, since it is no part of my present invention.

The variable speed reduction drive 24 has driving connection with a shaft 27, journaled in the housing 20, through a flexible coupling 28 (see

Figures 5 and 6). A chain and sprocket drive 29, within said housing, connects said shaft with the lower drum shaft 19, for driving said shaft. A pair of meshing spur gears 30 and a chain and sprocket drive 31 connects said shaft 27 with the upper drum shaft 19, for driving said shaft at the same rate of speed as the speed of rotation of said lower shaft. A hand wheel 32 is keyed to each shaft 19 to permit said shafts and collapsible blocks to be turned by hand to properly position said blocks for insertion of the leading ends of the coils in the slots 17, 17, and to properly position said blocks for removing the coils of strip metal therefrom.

Referring now to Figures 7 to 13 inclusive and certain details of construction of the collapsible blocks 11, 11, said blocks are each of a similar construction, so one only need herein be shown and described in detail. The lower block 11 is shown in detail in these figures and includes a drum segment 33 mounted on the shaft 19 on a plurality of spaced hubs 34, 34, herein shown as being keyed to said shaft. Said drum segment has a longitudinally extending relatively flat recessed portion 35, which leads to an arcuate outer periphery of said drum segment in an inclined direction. A shoe 36 is secured to said recessed portion 35 and extends outwardly along the inclined surface of said inclined portion to and along the outer periphery of said drum segments, and the portion extending along the outer periphery of said drum segment forms an outer surface for said drum segment (see Figures 8 and 9).

A plurality of collapsible drum segments 40 and 41 are pivotally connected to opposite sides of the drum segment 33 on transverse shafts 42 and 43 respectively. The space between the end of the drum segment 41 and the inclined portion of the shoe 36 is filled by a member 44 mounted on the outer side of a plurality of spaced blocks 45, 45 spaced along said drum and secured to said shoe, as by rivets 46, 46. Said member forms a continuation of the outer periphery of the drum and has an end 47, adjacent but spaced from the inclined portion 48 of the transverse shoe 36 a distance sufficient to form the slot 17, for the insertion of the strip metal. The lower inner portion of the inclined portion of the shoe 36 is provided with a longitudinally slotted portion 49, in alignment with the slot 17, to receive the leading ends of the strip metal.

The strips of metal are held to said drum by a plurality of engaging members 50, 50 engaging the leading ends thereof. A plurality of said engaging members are adapted to engage each strip of metal, and each set of said engaging members is pivotally mounted on a longitudinally extending bar 51, mounted at its ends on a pair of parallel spaced rocking arms 52, 52, secured to the transverse shaft 43. Said shaft extends longitudinally of said drum and is pivotally mounted in spaced lugs 54, 54, projecting outwardly from the recessed portion of said drum segment 33, and in end plates 55, 55 of said drum. Said shaft likewise extends through spaced lugs 53, 53 formed integrally with the drum segment 41 and extending along opposite sides of the lugs 54, 54, and is secured to said lugs 53, 53, so said arms 52, 52 will be rocked by said shaft upon rocking movement of the drum segment 41 during expansion or collapsing of the block, to move said engaging members 50, 50 to a released position, upon collapsing of the block. Leaf springs 56, 56, mounted on said arms, have engagement with said engaging members 50, 50, to release

them from the strip metal upon collapsing of the block and the movement of said arms 52, 52 in a direction away from the center of said block.

The drum segments 40 and 41 are pivoted about the axes of the shafts 42 and 43, to expand or collapse the drum, by means of a cam 57 journaled at its ends in the end plates 55, 55. Adjacent ends of said drum segments are held in engagement with said cam by means of a plurality of spaced tension springs 59, 59 connected at their ends to inwardly extending flanged portions of said drum segments.

The end of the shaft of the cam 57, on the outer side of said block, projects beyond the end plate 55 and is slotted to receive an end of a hand lever 60. Said hand lever is provided to turn said cam from the position shown in Figure 13, to the position shown in Figure 8, to expand the drum segments 40 and 41 and hold them in an expanded position; or to move said cam from the position shown in Figure 8 to the position shown in Figure 13, to permit said drum to be collapsed by tension of the metal wound thereon and by the springs 59, 59. Said hand lever is transversely pivoted to said end of said shaft by means of a pivotal pin 61 so it may be pivoted in an upward direction, when said cam is in either of the positions shown in Figures 8 or 13, to register for engagement with a notched locking plate 63 on the outside of the outer end plate 55, which serves to lock said hand lever in position.

The outer end plate 55 is slotted as is indicated by reference character 65 and the slotted portion thereof is in alignment with the slot 17, so the bent leading ends of the strip metal may pass therethrough, to permit removal of the coils from the end of the block upon collapsing of the block and the release of the clamping means which hold the leading ends of the strips to the block.

Referring now in particular to the push-off and spacing mechanism, for pushing the coils from the ends of the blocks 11, 11 onto the transfer car 14, a push-off plate 66 is provided. Said push-off plate, as herein shown, is supported on rollers 67, 67, which ride along the base frame 21 and which are mounted on brackets 68, 68, projecting from the lower end of said plate, in a direction towards the blocks 11, 11. Said plate extends vertically from said rollers to a position above the upper block 11, and is provided with two semi-circular recessed portions, which partially encircle said blocks as said plate moves therewith.

A pair of vertically spaced fluid cylinders 69, 69 are provided to move the push-off plate 66 across the faces of said blocks. Said cylinders are suitably secured to the housing 20 and have pistons 70, 70 movable therein, with piston rods 71, 71 extensible therefrom. Said piston rods are secured at their outer ends to the side of the push-off plate 66 opposite from said blocks.

A plurality of parallel vertically and horizontally spaced guide shafts 74, 74 extend horizontally from opposite sides of the push-off plate 66 and are suitably secured thereto, intermediate their ends, on hubs 75, 75 projecting from said plate in a direction away from the blocks 11, 11. Said guide shafts, as herein shown, are slidably guided in laterally spaced bearings 76, 76. The uppermost of said bearings is mounted in a pair of laterally spaced brackets 77, 77 projecting upwardly from the housing 20, while the intermediate shafts are mounted in laterally and vertically spaced brackets 78, 78 projecting rearwardly from said housing (see Figure 4). The lowermost

of said bearings is mounted in a pair of laterally spaced brackets 79, 79 depending from a base plate 80 of said housing.

The extreme upper shaft 74 and the second shaft 74 from the bottom have teeth cut on the forward sides thereof, which mesh with pinions 72, 72 on a vertically extending shaft 73, journaled in the frame 21. This forms a means for equalizing the travel of the piston rods 71, 71, so both piston rods will travel together.

The portions of said shafts which extend from the blocking side of the push-off plate 66 have a plurality of strip spacing and guiding members 81, 81 mounted thereon, which partially encircle the blocks 11, 11, on the side thereof adjacent the guide rolls 15, 15, and serve to guide alternate strips of metal onto said blocks and to hold said strips in spaced relation with respect to each other.

20 The upper spacing and guiding members 81, 81 are slidably mounted on the two upper guide shafts 74, 74 and are held in spaced relation with respect to each other by means of spacer sleeves 85, 85 and nuts 86, 86, threaded on the ends of said shafts. Said nuts abut collars 87, 87, which abut the end spacing and guiding members. Said spacer sleeves are of a length equal to substantially the width of the strip metal, to space said spacing and guiding members apart a distance 25 equal to substantially the width of the strip metal it is desired to wind on said blocks, it being understood that different widths of spacer sleeves are provided for different widths of metal.

25 The lower spacing and guiding members 81, 81 are mounted on the two lower shafts 74, 74 in the same manner the upper spacing and guiding members are mounted on the two upper shafts, and are of a construction similar to the upper spacing and guiding members but are spaced 30 between said upper spacing and guiding members, to guide alternate strips of metal onto said upper and lower blocks. Said lower spacing and guiding members are supported in reversed relation with respect to said upper spacing and guiding members, so the same guiding parts of said lower spacing and guiding members will adjoin the same parts of said upper spacing and guiding members.

35 As herein shown, each spacing and guiding member 81 includes a pair of spacer plates 89, 89 spaced apart by a ring segment 91, herein shown as being formed integrally with sleeves 92, 92, mounted on the shafts 74, 74. Each of said spacer plates has a semi-circular cut-out portion which partially encircles the block 11, and said ring segment is herein shown as being of a slightly larger diameter than the cut-out portions of said spacer plates.

40 A hold-down means is provided for said upper and lower drums, to hold the wound coils from unwinding. Said hold-down means, as herein shown, includes a transversely extending hold-down shoe 93 mounted on the ends of spaced arms 94, 94 and movable to a position to engage each coil on the block. Said arms are mounted on squared shafts 95, 95 extending parallel to the faces of said drums. Said upper and lower squared shafts are mounted in vertically spaced brackets 96, 96 formed from supporting angles 45 which project from the push-off plate 66 in directions along the blocks 11, 11, one of said brackets being disposed adjacent each of said blocks. Said shafts are journaled at their outer ends in said brackets and intermediate their ends 50 in said push-off plate, and project from said plate

in a direction away from said blocks. As shown in Figures 2 and 14 of the drawings, the upper hold-down projects upwardly from its respective shaft 95, while the lower hold-down projects downwardly from its respective shaft.

The means for turning the squared shafts 95, 95 and for operating the hold-down shoes 93, 93 includes arcuately formed arms 97, 97, one of said arms being mounted on each of said shafts and being disposed adjacent the brackets 78, 78 projecting from the housing 20. Said arms are herein shown as being mounted between the blocking side of the side walls of said brackets 78, 78 and restraining brackets 98, 98, secured to and projecting from the blocking sides of said side walls. Said restraining brackets serve to restrain said arms from rectilinear movement when the coils are pushed from the blocks 11, 11 by rectilinear movement of the push-off plate 66 and the spacing and guiding members 81, 81 along said blocks.

The adjacent ends of the arcuate arms 97, 97 have teeth cut therein and are in the form of an arcuate segment of a gear. Said teeth are meshed with teeth on opposite sides of a rack bar 99, slidably mounted on the side wall of the housing 20, which is disposed adjacent the blocks 11, 11. Said rack is provided with an upturned outer gripping end 100, adapted to be engaged by the hand so that movement of said rack will pivot the shafts 95, 95 and engage the hold-downs with or disengage them from the coiled strip metal. A pawl and ratchet indicated generally by reference character 101 is provided to hold said rack in position (see Figure 2).

The transfer car 14 includes an upright frame 107 provided with parallel spaced depending legs 108, 108, upon which are mounted supporting and guiding rollers 109, 109. Said rollers ride along and extend within the insides of the webs of a pair of parallel spaced channels 110, 110, which extend transversely of the blocks 11, 11, along the blocking side thereof (see Figures 2, 3 and 4). A pair of parallel spaced guide strips 111, 111, mounted on and projecting upwardly from a plate 112 extending between and along said channels, are provided to engage the insides of the legs of said frame and serve as a guide means for said transfer car (see Figures 3 and 4).

The means for moving said transfer car 14 along the track formed by the channels 110, 110 includes a fluid pressure cylinder 113 having a piston rod 114 extensible therefrom (see Figure 3). Said piston rod is connected at its forward end to a bracket 115 depending from the forward end of said transfer car, so that movement of said piston rod in one direction or another, caused by the admission of fluid pressure into one end or the other of said cylinder, will move said transfer car in a like manner.

The coils of metal are supported on the transfer car 14 on coil supporting sectors 116, 116, mounted on shafts 117, 117. Said shafts are mounted in the upright frame 107 and extend towards the blocks 11, 11 and are so positioned on said frame as to be coaxial with the shafts 19, 19, when said transfer car is in position to receive coils from said blocks 11, 11. As herein shown, said coil supporting sectors and shafts are held from turning movement by means of wedge-shaped keys 118, 118, extending through said shafts and supporting hubs 119, 119, which hubs are formed integrally with said frame and extend therefrom in a direction from the blocks 11, 11 (see Figure 3).

The outer sides of the coil supporting sectors

116, 116 are in the form of sectors of circles of substantially the same diameter as the diameter of the blocks 11, 11, and the outer ends of said sectors are abutted by circular plates 120, 120, which are secured thereto. A pin 121 is secured to and projects rearwardly from each of said plates and a key 122, extending through said pin and abutting the outer side of the frame 107, holds said pin and plate to said frame. Each of said coil supporting sectors is provided with a slotted portion 123 at its upper end, for the insertion of a lifting means, so the coils may be readily removed from said sectors.

A hold-down means is provided adjacent each coil supporting sector 116, to hold the trailing ends of the coils on said coil supporting sectors (see Figure 2). Each of said hold-downs includes a pair of laterally spaced lever arms 124, 124 having a hold-down shoe 125 connected therebetween, on the outer ends thereof. Said lever arms are mounted on vertically spaced horizontal transversely extending shafts 126, 126, which are journaled in the frame 107. The means for operating said hold-downs includes a hand lever 127 secured to the lower of said shafts. A link 128 connected between the outer ends of lever arms 128, 128, secured to said shafts, serves to connect said shafts for operation together so that movement of said hand lever in a direction towards the sectors 116, 116 will simultaneously engage the upper and lower hold-down shoes 125, 125 with their respective coils.

The collapsible guide plate 16 is transversely hinged intermediate its ends and is mounted at its rear on a transverse shaft 130 suitably mounted in a frame 131, for the guide rolls 15, 15 (see Figure 2). The underside of the front end of said guide plate is beveled, and the beveled portion thereof slidably engages the upper sides of the lower spacer plates 89, 89, and when in a collapsed position, is supported by an upright supporting member 132, projecting upwardly from the base frame 21.

The means for extending said guide plate includes an arm 133 secured to the transverse shaft 130 and projecting angularly forwardly and upwardly therefrom. A link 134 is pivotally connected to the free end of said arm and depends therefrom. The lower end of said link is pivotally connected with one end of a foot operated lever 135, pivoted intermediate its ends to the base frame 21 and adapted to be operated by foot pressure on its end opposite from said link. When the foot lever 135 is depressed, the guide plate 16 will be extended to the position shown in Figure 2, to permit strip to pass thereover and be attached to the blocks 11, 11 in the hereinbefore described manner, and when foot pressure is relieved from said lever, said guide plate will collapse to the position shown by broken lines in Figure 2 and will be out of the way of the strips of metal as they are wound on their respective blocks.

In operation, the strips of metal are trained over the guide roll 15 between the spacing and guiding members 89, 89 so they may be alternately connected at their free ends to the blocks 11, 11 by insertion of the ends thereof in the slots 17, 17 of said blocks, as desired.

It should here be noted that as the strip metal is slit, the edges of alternate strips of metal are burred in upward and downward directions. In coiling the metal it is desirable that the burrs of all of the coils extend in the same direction. Thus if it is desired that the burrs be on the

insides or outsides of the coils, alternate strips are attached to either the upper or lower drums. As for example, if the burr on the first strip extends from the lower edge of said strip and it is desired that the burrs be on the inside of the coil, the first strip is connected to and wound on the lower block 11, which rotates in a counter-clockwise direction; the second strip is connected to and wound on the upper block 11 which rotates in a clockwise direction; the third strip is connected to and wound on the lower block, and so on.

When the slit strips of metal have been connected to their respective blocks, foot pressure is removed from the lever 135 and the guide plate 16 is collapsed so as to be out of the way of the strip metal. The motor 23 is then started to rotatably drive the blocks 11, 11 and wind the strip metal thereon. The speed of winding of said blocks is automatically controlled by the vari-torque coupling 25 in a well known manner, to vary in accordance with the torque exerted by said blocks and to provide a substantially constant pull on the strip metal during the entire winding operation. When the strips of metal are fully wound on their respective blocks, the hold-down shoes 93, 93 are engaged with the free ends thereof and the transfer car 14 is moved by the cylinder 113 to a position where the coil supporting sectors 116, 116 are in alignment with the blocks 11, 11. At this time, said blocks may be turned by the hand wheels 32, 32 until the slots 65, 65 are beneath said coil supporting sectors, so the coils may be slidably moved from the ends of said blocks onto said sectors, and the bent-over leading ends of the coils will be free from said sectors. Fluid under pressure, such as air, may then be admitted to the head ends of the fluid cylinders 69, 69, to cause the push-off plate 66 and the spacing and guiding members 81, 81 to move the coils from the ends of said blocks onto said coil supporting sectors. As said coils are transferred onto said sectors, and before the hold-down shoes 93, 93 are released, the hold-down shoes 125, 125 on the transfer car 14, which face the hold-down shoes 93, 93, are engaged with said coils, to prevent their unwinding. The hold-down shoes 93, 93 are then released and fluid under pressure may then be admitted to the head end of the cylinder 113 to move said transfer car and coils away from said blocks, the hold-down shoes 125, 125 still being in engagement with said coils. When said transfer car has been moved away from said blocks by said cylinder and the piston rod 114, the individual coils may be banded to prevent their unwinding, and the hold-down shoes 125, 125 may then be released. Bars or hooks may then be inserted in the slots 123, 123 and chains connected with a suitable lifting device, such as a crane, may be attached to said bars or hooks, for lifting the coils from said sectors, for storage or further processing.

While we have herein shown and described one form in which our invention may be embodied, it will be understood that the construction thereof and the arrangement of the various parts may be altered without departing from the spirit and scope thereof. Furthermore, we do not wish to be construed as limiting our invention to the specific embodiment illustrated, excepting as it may be limited in the appended claims.

We claim as our invention:

1. In a coil blocking and handling apparatus, a plurality of vertically spaced coiling blocks

adapted to have clamping engagement with the leading ends of a plurality of strips of metal, coil transferring mechanism adapted to receive and support the coiled strip metal, and means for guiding the strips of metal onto said blocks in spaced apart relation with respect to each other and for pushing the coils from said blocks in an endwise direction onto said coil transferring mechanism including a push-off plate movable along said blocks, and spacing members mounted on said push-off plate and movable therewith, for spacing the strip metal as it is wound on said blocks and for pushing the coils of metal from said blocks onto said coil transferring mechanism in a definite spaced relation.

2. In a coil blocking and handling apparatus, a plurality of vertically spaced coiling blocks adapted to have clamping engagement with the leading ends of a plurality of strips of metal and to simultaneously wind said strips of metal into coils, coil transferring mechanism adapted to receive and support the coiled strip metal, means for guiding the strips of metal onto said blocks in spaced apart relation with respect to each other and for pushing the coils from said blocks in an endwise direction onto said coil transferring mechanism including a push-off plate disposed along one end of said blocks, spacing members mounted on said push-off plate and movable therewith, for spacing the strip metal as it is wound on said blocks and for pushing the coils of metal from said blocks in spaced apart relation with respect to each other, and means for moving said push-off plate and spacing members across the faces of said blocks, for transferring the coils therefrom onto said transferring mechanism.

3. In a coil handling apparatus and in combination with a plurality of spaced power driven blocks adapted to simultaneously wind a plurality of parallel spaced strips of metal thereon, a push-off plate extending along one end of said blocks, a plurality of parallel spaced spacing members mounted on said push-off plate and spaced from the blocking side thereof, said spacing members extending partially around said blocks and substantially conforming to the form thereof, and means for moving said push-off plate and spacing members along the faces of said blocks, for removing said coils from the ends thereof in spaced relation with respect to each other.

4. In a coil handling apparatus and in combination with a plurality of spaced power driven blocks adapted to simultaneously wind a plurality of parallel spaced strips of metal thereon, a push-off plate extending along one end of said blocks, a plurality of parallel spaced spacing members mounted on said push-off plate and spaced from the blocking side thereof along said blocks, said spacing members extending partially around said blocks and substantially conforming to the form thereof, means for moving said push-off plate and spacing members across the faces of said blocks, for removing said coils from the ends thereof in spaced relation with respect to each other, and coil transferring mechanism adapted to receive and transfer said coils for further processing including a plurality of coil supporting sectors movable to a position in alignment with said blocks.

5. In a coil handling apparatus and in combination with a plurality of spaced power driven blocks, adapted to simultaneously wind a plurality of parallel spaced strips of metal thereon,

a push-off plate extending along one end of said blocks, a plurality of parallel spaced spacing members mounted on said push-off plate and spaced from the blocking side thereof, along said blocks, said spacing members extending partially around said blocks and substantially conforming to the form thereof, means for moving said push-off plate and spacing members across the faces of said blocks for removing said coils from the ends thereof, and hold-down means mounted on said push-off plate and manually operable to engage the trailing ends of the strips of metal, to hold said ends of the strips of metal from uncoiling during transfer from said blocks.

6. In a blocker and coil handling apparatus, a power driven coiling block having a longitudinally extending slotted portion for receiving the leading end of a strip of metal and having clamping means therein for clamping the leading end of the strip of metal during the winding operation, said slotted portion opening to one side of said drum to permit the coil of metal to be removed from the end thereof without first removing the leading end of the metal from said slot, a coil transferring and guiding device adapted to guide a strip of metal onto said block and to push the wound coil from the end of said block including a push-off plate adapted to extend along one end of said block during the winding operation and movable along the face of said block to the opposite end thereof, for removing the coiled metal from said block, a hold-down shoe mounted on said push-off plate, on the blocking side thereof, for engagement with the coil of metal, to hold the coil from unwinding, during removal from said block, a coil transfer car having a coil supporting sector mounted thereon and adapted to be moved into alignment with said block to receive and support the coil of metal discharged from said block, and a hold-down shoe on said transfer car adapted to engage the coil of metal during engagement of the coil with said other hold-down shoe, to hold down the coil during movement of said transfer car away from said coil transferring and guiding device and said other hold-down shoe.

7. In a blocker and coil handling apparatus, a coiling block having a slotted portion extending along the face thereof adapted to have the leading ends of a plurality of parallel spaced strips of metal inserted therein, means for clamping said ends of said strips to said block, but permitting the coils to move along said block beyond the end thereof upon collapse of said block and release of said clamping means, and a coil transferring and guiding device adapted to guide the strips of metal onto said block in parallel relation with respect to each other and to push said wound coils from the end of said block including a push-off plate guided for movement along the face of said block, means for moving said push-off plate along the face of said block, a plurality of strip guiding and spacing members, spaced from the blocking side of said push-off plate and mounted thereon for movement therewith, for guiding a plurality of strips of metal onto said block in spaced relation with respect to each other and for removing the coiled strips therefrom upon movement of said push-off plate across the face of said block, and means for receiving and transferring the coils discharged from the ends of said block including a coil supporting sector movable to a position in alignment with

said block, for receiving the coils transferred from said block by said push-off plate and said spacing and guiding members, hold-down means mounted on said push-off plate and manually operable to engage the trailing ends of the strips of metal, to hold said ends from uncoiling until the coils are transferred onto said coil supporting sector, and other hold-down means mounted on said coil transferring means and facing said first mentioned hold-down means, for engaging the coiled metal and holding down the ends thereof while said first mentioned hold-down means is still in engagement with said coils, and during movement of said coils away from said first mentioned hold-down means.

8. In a blocker and coil handling apparatus, a coiling block having a longitudinally extending slotted portion for receiving the leading end of a strip of metal, clamping means within said block for clamping the leading end of the strip of metal during the winding operation, said slotted portion opening to one side of said block to permit the leading end of the metal to be moved along said slotted portion and to permit the coil of metal to be removed from the end of said block upon collapse of said block and release of said clamping means, a coil transferring and guiding device adapted to guide a strip of metal onto said block and to push the wound coil from the end of said block including a push-off plate adapted to extend along one end of said block during the winding operation and movable along the face of said block towards the opposite end thereof, for removing the coiled metal from said block, a guiding member spaced from said push-off plate and adapted to engage the edge of the metal opposite from said push-off plate and cooperate with said push-off plate to guide the metal onto said block, said guiding member being movable with said push-off plate to hold the coiled metal from springing laterally during removal of the coil from said block, a pivoted hold-down shoe mounted for movement with said push-off plate and guiding member and engageable with the coil of metal, for holding the coil from unwinding during removal from the end of said block, a coil transfer car having a coil supporting sector mounted thereon and adapted to be moved into alignment with said block to receive and support the coil of metal discharged from said block, and a hold-down shoe on said transfer car adapted to engage the coil of metal during engagement of the coil with said other hold-down shoe, to hold down the coil during movement of said transfer car away from said coil transferring and guiding device and said other hold-down shoe.

LOUIS LEROY.
